Primary Examiner—T. Chase Nelson*Assistant Examiner*—David G Muller(74) *Attorney, Agent, or Firm*—Hunton & Williams LLP(57) **CLAIM**

We claim the ornamental design for a transaction device, as shown and described.

DESCRIPTION

FIG. 1 depicts a perspective view of a front face of a transaction device;

FIG. 2 depicts a front elevation view of FIG. 1;

FIG. 3 depicts a back elevation view of FIG. 1;

FIG. 4 depicts a side elevation view of FIG. 1;

FIG. 5 depicts an opposite side elevation view of FIG. 1;

FIG. 6 depicts a bottom plan view of FIG. 1; and,

FIG. 7 depicts a top plan view of FIG. 1.

The broken lines in the drawings illustrate environmental structure on the article and form no part of the claimed design.
